UNITED STATES PATENT OFFICE

104,188

DESIGN FOR A MULTIPLE COLUMN RADIATOR

Lurelle A. V. Guild, Darien, Conn., assignor to
National Radiator Corporation, Johnstown,
Pa., a corporation of Maryland

Application February 19, 1937, Serial No. 67,748

Term of patent 14 years

To all whom it may concern:

Be it known that I, Lurelle A. V. Guild, a citizen of the United States, residing at Darien, Fairfield County, Connecticut, have invented a certain new, original, and ornamental Design for a Multiple Column Radiator, of which the following is a specification, reference being had to the accompanying drawing, forming a part thereof.

In the drawing:

Figure 1 is an end elevation of a multiple column radiator embodying my design;

Figure 2 is a side elevation thereof; and

Figure 3 is a sectional view in the plane of line III—III of Figure 1.

I claim:

The ornamental design for a multiple column radiator, as shown.

LURELLE A. V. GUILD.
